UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,352,447.

Specification of Letters Patent. Patented Sept. 14, 1920.

Application filed December 20, 1916. Serial No. 133,004.

To all whom it may concern:

Be it known that I, ARTHUR J. HALL, a subject of the King of Great Britain, and a resident of Wilkinsburg, in the county of 5 Allegheny and State of Pennsylvania, have invented a new and useful Improvement in Control Apparatus, of which the following is a specification.

My invention relates to control apparatus 10 and especially to certain structural features of liquid rheostats and the like.

One object of my invention is to provide a polyphase liquid rheostat embodying sets 15 of electrodes of different lengths for the several phases, the electrodes being arranged in an irregular rotation of phases and of lengths in such manner that substantially equal active areas corresponding to the several phases are immersed at all liquid 20 levels, whereby a relatively smooth and gradual exclusion of circuit resistance is effected.

More specifically stated, it is the object of 25 my invention to provide a plurality of electrodes or plates of the above-indicated character arranged in side-by-side relation in such manner as to include, at all times, equal total volumes of electrolyte between plates of different phases, the successive increments 30 of volume, as the liquid level rises, gradually decreasing in size but remaining equal in the respective phases, whereby a relatively smooth accelerating curve for a locomotive or train is obtained, and no sudden jumps 35 or jerks are experienced by reason of an unduly great change of resistance value in the rheostat, or a too sudden decrease in the distance between plates, as the liquid level rises.

40 A further object of my invention is to provide a relatively simple, but compact and durable, means for supporting a plurality of electrodes and connecting them to an external polyphase circuit.

45 Still another object of my invention is to provide means, preferably in the form of porcelain spools, arranged in such manner that the splashing or trickling of liquid from any electrode to a conducting part 50 that is connected with any other electrode is completely prevented.

55 My invention may best be understood by reference to the accompanying drawings, wherein Figure 1 is a view, in side elevation, with parts broken away for clearness, of a

plurality of electrodes arranged and supported in accordance with my present invention within a tank that is shown in section; Fig. 2 is a sectional view taken along the line II-II of Fig. 1; and Fig. 3 and 60 Fig. 4 are fragmentary sectional views, similar to Fig. 2, and respectively taken along the lines III-III and IV-IV of Fig. 1.

Referring to the drawings, the liquid rheostat shown comprises a suitable containing tank 1; a bottom discharge reservoir 2; a suitable inlet means 3 and an appropriate outlet means 4, located at the respective ends of the tank 1; a plurality of plates or electrodes 5 that are arranged 65 in a novel manner to be described; a plurality of insulated conducting and supporting means 6 for the several electrodes 5; and flexible conducting means 7 for suitably connecting the several electrode terminal 70 members to the desired external circuits.

Inasmuch as the structural details of the containing tank are immaterial to my present invention, a very simple structure is shown, but it will be understood that any 80 suitable type of containing tank and inlet and outlet means may be employed. The preferable structures are fully set forth and claimed in my copending application Serial No. 134,610, filed Dec. 2, 1916, which, among 85 other things, discloses a suitable vertically movable valve that operates within the discharge opening 4 to vary the liquid level, and in another co-pending application of C. C. Whittaker, Serial No. 134,762, filed 90 Dec. 2, 1916, and assigned to the Westinghouse Electric & Manufacturing Company.

The electrodes 5 correspond to three different phases, which may be conveniently designated as A, B, and C, respectively, and 95 are of five different lengths, considered from the marked maximum or final liquid level to the electrode tips, namely, a, b, c, d and e, as indicated in Fig. 2. The two outer plates correspond to phase A and are of somewhat 100 smaller size than the corresponding intermediate plates for the phases B and C, as best shown in Fig. 1, in order to provide substantially the same electrical effect, that is, a balanced resistance arrangement, in accordance with a familiar practice. The external surfaces of the two outer or longest plates corresponding to phase A are practically inactive electrically, and, in discussing the operation of the rheostat, only the 105 110

two inner faces of the outer plates in question will be considered as active. The arrangement of electrodes with respect to the phases and lengths, in accordance with the 5 previous designations, may be listed as follows: *Aa, Cd, Ac, Bb, Ce, Ba, Ad, Bc, Cb, Ae, Ca, Bd, Cc, Ab, Be, Aa*. Such an irregular rotation of phases and of lengths provides a relatively smooth exclusion of 10 the rheostat resistance from circuit, as subsequently described in detail.

Each electrode 5 is provided with a number of relatively small apertures 10 and with twice that number of relatively large apertures 11. A corresponding number of 15 transversely-extending rods 12 (in this case, two pairs of two rods per phase to thereby prevent rotative movement of parts) of conducting material fit within the respective 20 sets of aligned small apertures of all plates of the same phase and pass through the larger openings of all other electrodes corresponding to the other two phases, whereby 25 only plates of the same phase are supported by, and electrically connected to, any one rod. A plurality of conducting sleeves 13 of various appropriate lengths surround the 30 various portions of each rod between the successive plates of the same phase, while insulating spools 14, of porcelain or other suitable material, inclose the sleeve members 13 within the larger apertures 11 of the plates belonging to the other phases. For example, 35 in Fig. 2 the rods 12 are shown as supporting all the plates of phase B, while, in Fig. 3 and Fig. 4, corresponding constructions for electrodes of phase A and of phase C, respectively, are illustrated.

The purpose of the insulating spools 14 40 is to effectively prevent trickling of liquid from each plate to a conducting sleeve or rod corresponding to a different phase, with the consequent short-circuiting of plates. Such trickling naturally results from the 45 inevitable splashing and shifting of liquid level that occurs in moving locomotives or cars and especially from boiling and bubbling at high temperatures. It is particularly desirable to prevent such trickling and 50 consequent liability to disadvantageously vary the rheostat resistance during the lower liquid levels. Under high-level conditions, the resistance between phases is, of course, greatly diminished, and the results of lack 55 of protection from the trickling action in question would not be so serious. The use of such insulating means, however, is a very decided advantage, considering rheostatic operation as a whole.

60 A plurality of yoke members 15 (in this case six members) severally have two apertures in each vertical arm that fit over the ends of the vertically-assembled pairs of rods 12 corresponding to the respective 65 phases.

For the purpose of rigidly positioning the plates of the individual phases, the ends of the corresponding rods 12 are threaded and are provided with suitable nuts 16 and lock washers 17, whereby the metallic sleeve members 13 are caused to make good electrical contact with the corresponding electrodes and yoke members.

The yoke members 15 are suitably secured, by means of bolts 18, for example, to cap 75 members 19 of suitable insulators 20, one pair of oppositely-facing insulators being employed for each yoke member. The bases 21 of the insulators are attached to longitudinally-extending angle members 22 80 through the agency of bolts 23. The ends of the angle members 22 are supported upon transversely-extending angle-irons 24, which may be welded, or otherwise suitably secured, to the end walls of the tank 1. A plurality of transversely-extending intermediate brace members 25 may also be secured to the respective angle members 22 to lend additional rigidity to the electrode supporting structure. 90

The positions of the several bolt-holes corresponding to the bolts 18 determine the position of the plate groups of the respective phases with respect to the provision of equal distances between electrodes. The 95 clamping parts of the several insulators are so designed as to provide a certain degree of "universal movement" to facilitate assembly and impose a minimum permanent strain upon the insulators, as fully set forth 100 and claimed in my co-pending application, Serial No. 173,466, filed June 8, 1917, which has matured into Patent No. 1,262,784, granted April 16, 1918.

In order to shunt or divert a portion of 105 the electric current from the rods 12 and the sleeve members 13, a plurality of double strap members 28, 29 and 30 also shown in the broken-away portion of Fig. 1 are severally provided with apertures that fit over 110 the corresponding rods 12 and make contact with two intermediate plates of the same phase. Fig. 3 shows the strap member 30 alone as connected to two plates of phase 115 A, while Fig. 4 illustrates the strap member 28 alone as connected to two electrodes of phase C. The strap member 29, corresponding to phase B, may be readily observed from Fig. 2 by process of elimination and in form is identical with the strap 120 member 28.

The strap members 28, 29 and 30 are suitably spaced apart and extend upwardly to be clamped or otherwise suitably secured to the central portions of the corresponding 125 yoke members 15, while an equal number of conducting bus-bar members 31, 32 and 33 are also secured to the respectively corresponding yoke members. The central bus-bar member 31 is of a simple right-angle 130

form and its horizontal arm extends beyond the outer insulators 20 to make suitable connection with the flexible conducting means 7, as hereinafter more completely set forth. To 5 suitably laterally space the other bus-bar members 32 and 33 from the intermediate bus-bar 31, the vertical portions of the bar members 32 and 33 are transversely curved in opposite directions before being clamped 10 to the corresponding yoke members 15, as clearly shown in Fig. 2. Each of the bus-bars 32 and 33 likewise is of appropriate length to extend to the flexible conducting means 7.

15 Another set of bus-bar members 34, 35 and 36, which differ from the members just described substantially only in the length of their horizontal portions, extends from the left-hand group of insulators 20 (Fig. 1), 20 and the horizontal portions in question rest upon the horizontal portions of the other bus-bar members and terminate at the same point. To provide for expansion of the relatively long bus-bar members 34, 35 and 36 25 under heated operating conditions, a dip or loop 50 is located intermediate the ends of the members in question.

The flexible conducting means 7 corresponding to each phase comprises a flexible 30 rope or cable 37 of copper, for example, having suitable lugs or terminal members 38 and 39 electrically secured to its respective ends. The terminal member 38 is attached by means of a plurality of bolts 40 to the outer ends of 35 the several bus-bar members 31 to 36, inclusive, while the other terminal member 39 incloses a threaded rod or other appropriate conducting means 41 that is embedded in a suitable insulating bushing 42 that extends 40 through an adjacent portion of the tank wall. A plurality of suitable nuts 43 may be employed for effecting proper electrical contact between the terminal member 39 and the threaded rod 41. Each bushing 45 42 may be attached to the tank wall in any appropriate manner, as by a plurality of bolts 44, and the outer end of its conducting member 41 is provided with a terminal member 45 and positioning nuts 46 for the purpose 50 of effecting connections to the desired external circuits. Thus, the electrodes and their immediate connecting means are flexibly associated with the external circuits to relieve the electrode and bushing structures 55 from shocks and jars incidental to railway service.

The action of the liquid rheostat may be best explained by considering the rise in liquid level, accomplished in any suitable 60 manner from a normal plane below the electrodes to the plane marked "Maximum level." In the first place, let the portions of electrolyte between confronting portions of plates corresponding to phases A and B be 65 designated as x , between phases B and C as

y , and between phases C and A as z . Then, upon the rise of liquid level from the dotted line corresponding to the dimension a to the next higher dotted line corresponding to the dimension b , it will be observed that 70 equal and relatively large volumes of electrolyte, respectively marked x , y and z , are included between the active confronting portions of the electrodes. As hereinbefore stated, the external faces of the outermost 75 electrodes, which both correspond to phase A, are considered as totally inactive for the purposes of the present specification.

As the liquid level gradually rises from the dotted line corresponding to the dimension b to the next higher line corresponding to the dimension c , again equal volumes of electrolyte, respectively marked x , y and z , are included between the active confronting areas of plates corresponding to different 80 phases. Furthermore, inactive volumes of electrolyte, respectively marked a' , b' and c' , are included between confronting portions of pairs of plates corresponding to the phases A, B and C, respectively, which portions are, consequently, inactive. The areas corresponding to the volumes a' , b' and c' are cross-hatched in Fig. 2 for the sake of clearness and convenience.

A further rise of liquid level to the dotted 95 line corresponding to dimension d again causes the insertion in circuit of equal blocks of electrolyte, respectively marked x , y and z , and the formation of inactive volumes of electrolyte, respectively marked a' , b' and c' , as will be understood without further description.

Analogous results follow upon the rise of liquid level to the dotted line corresponding to the dimension e , whereby three sets 105 of active blocks of electrolyte, namely z , z and x ; x , x and y ; and y , y and z are introduced into the circuit. Thus, equal active areas corresponding to the various phases are again submerged, although such areas 110 are not located in accordance with a regular rotation of phases. By causing the liquid level to rise toward the plane marked "Maximum level," three further sets of active volumes of electrolyte, namely, y , y ; 115 z , z ; and x , x , as shown in Fig. 2, are inserted in the circuit.

It will be seen that I have thus provided a liquid rheostat wherein the electrodes, corresponding to the several phases and of five 120 different lengths, are arranged in an irregular rotation of phases and of lengths in such manner that unequal sets of active electrolyte volumes are successively included in circuit to thereby gradually reduce the active resistance value of the rheostat, but the blocks of liquid corresponding to each phase are equal in each particular set, whereby the exclusion of resistance from each phase of the circuit is, at all times, equal. Stated in 125 130

another way, the submerged active electrode areas of confronting electrodes of different phases and also the immersed inactive confronting areas corresponding to the same phases, are respectively equal for each phase below all planes at right angles to the electrodes, that is to say, at all liquid levels.

One of the principal reasons for the smooth resistance-exclusion or acceleration curve that is effected by the use of rheostats constructed in accordance with the present invention, is the location of the second set of active plates a greater distance from the confronting areas of active plates of different phases than from the confronting areas of plates of the same phase, whereby the exclusion of a relatively large step of resistance and a consequent jump or jerk of the accelerating car or locomotive is prevented, by reason of the fact that a properly proportioned volume of electrolyte is excluded at this time with the result that the desired smooth accelerating curve is maintained.

I do not wish to be restricted to the specific structural details or arrangement of parts herein set forth, as various modifications thereof may be effected without departing from the spirit and scope of my invention. I desire, therefore, that only such limitations shall be imposed as are indicated in the appended claims.

I claim as my invention:

1. A polyphase liquid rheostat embodying sets of electrodes of different lengths for the several phases, the electrodes being arranged in an irregular rotation of phases in such manner that substantially equal active areas corresponding to the several phases are immersed at all liquid levels.

2. A polyphase liquid rheostat embodying sets of electrodes of different lengths for the several phases, the electrodes being arranged in an irregular rotation of phases in such manner that substantially equal active areas and substantially equal inactive areas between the outermost electrode surfaces, respectively, corresponding to the several phases are immersed at all liquid levels.

3. A polyphase liquid rheostat embodying sets of electrodes of different lengths for the several phases, the electrodes being arranged in an irregular rotation of phases in such manner that, upon a predetermined rise of liquid level, an additional group of electrodes, each respectively located nearer to an electrode of similar phase than to an active electrode of a different phase, is immersed.

4. A polyphase liquid rheostat embodying sets of electrodes of different lengths for the several phases, the electrodes being arranged in spaced side-by-side relation in an irregular rotation of phases in such manner as to provide substantially equal areas corresponding to the several phases and con-

fronting electrodes of other phases below any plane intersecting the electrodes at right angles.

5. A polyphase liquid rheostat embodying sets of electrodes of different lengths for the several phases, the electrodes being arranged in spaced side-by-side relation in an irregular rotation of phases in such manner as to provide substantially equal areas corresponding to the several phases and confronting electrodes of other phases below all planes extending at right angles to the electrodes and also to provide substantially equal areas corresponding to the several phases confronting electrodes of the same phases below any plane intersecting the electrodes at right angles.

6. A polyphase liquid rheostat embodying sets of electrodes of different lengths for the several phases, the electrodes being arranged in spaced side-by-side relation in an irregular rotation of phases in such manner as to include between confronting electrode portions of different phases substantially equal cubical spaces irrespective of the number of electrode lengths utilized.

7. A polyphase liquid rheostat embodying sets of electrodes of different lengths for the several phases, the electrodes being arranged in spaced side-by-side relation in an irregular rotation of phases in such manner as to include between corresponding groups of confronting electrode portions of different phases substantially equal liquid volumes, the successive increments of volume gradually decreasing in size as the liquid level rises to thereby produce a gradually decreasing resistance value between phases.

8. A polyphase liquid rheostat embodying sets of electrodes of different lengths for the several phases, the electrodes being arranged in spaced side-by-side relation in the following manner, A, B and C representing the respective phases and *a*, *b*, *c*, *d* and *e* indicating the different lengths: *Aa*, *Cd*, *Ac*, *Bb*, *Ce*, *Ba*, *Ad*, *Bc*, *Cb*, *Ae*, *Ca*, *Bd*, *Cc*, *Ab*, *Be*, *Aa*.

9. A polyphase liquid rheostat embodying sets of electrodes of different lengths for the several phases, the electrodes being arranged in insulated and equally spaced side-by-side relation in the following manner, A, B, and C representing the respective phases and *a*, *b*, *c*, *d* and *e* indicating the different lengths in the decreasing order: *Aa*, *Cd*, *Ac*, *Bb*, *Ce*, *Ba*, *Ad*, *Bc*, *Cb*, *Ae*, *Ca*, *Bd*, *Cc*, *Ab*, *Be*, *Aa*.

10. In a polyphase liquid rheostat, the combination with a plurality of sets of electrodes corresponding to the several phases, of a corresponding plurality of conducting members respectively supporting only electrodes of the same phase, and insulating means interposed between each conducting member and all other electrodes.

11. In a polyphase liquid rheostat, the

- combination with a plurality of sets of electrodes corresponding to the several phases and severally provided with a relatively small and a plurality of relatively large 5 apertures, of a corresponding plurality of conducting members respectively fitting in said small apertures of electrodes of the same phase and passing through the large apertures of the other electrodes, and a plurality 10 of insulating members surrounding the conducting members within and on either side of said large apertures.
12. In a polyphase liquid rheostat, the combination with a plurality of sets of electrodes corresponding to the several phases and severally provided with a relatively small and a plurality of relatively large 15 apertures, of a corresponding plurality of conducting rod members respectively fitting in said small apertures of electrodes of the same phase and passing through the large apertures of the other electrodes, a plurality 20 of conducting sleeve members surrounding each of said conducting rod members between the electrodes of the same phase, a plurality 25 of sleeve members for suitably insulating said conducting rod members, and means for securing good electrical contact between the electrodes and the corresponding 30 conducting sleeve members.
13. In a polyphase liquid rheostat, the combination with a plurality of sets of electrodes corresponding to the several phases, of a corresponding plurality of conducting 35 means respectively connected only to electrodes of the same phase, and means for preventing the trickling of liquid from the electrodes upon conducting means of a different phase.
- 40 14. In a polyphase liquid rheostat, the combination with a plurality of sets of electrodes corresponding to the several phases, of a corresponding plurality of transversely-extending conducting members connected 45 only to electrodes of the same phase, means connected to the ends of the respective conducting members for conducting current thereto, and a plurality of other conducting means interposed between said last means 50 and an intermediate electrode of the corresponding phase.
15. In a polyphase liquid rheostat, the combination with a plurality of sets of electrodes assembled in spaced side-by-side relation and corresponding to the several 55 phases, of a corresponding plurality of transversely-extending conducting members connected only to electrodes of the same phase, conducting yokes connected to the 60 ends of the respective conducting members, insulating means for supporting the respective yokes, laterally spaced conducting bars attached to the respective yokes, and a plurality of other conducting means inter- posed between said yokes and certain intermediate electrodes of the corresponding phase.
16. In a polyphase liquid rheostat, the combination with a plurality of sets of electrodes assembled in spaced side-by-side relation and corresponding to the several phases, of a corresponding plurality of transversely-extending conducting members connected only to electrodes of the same phase, conducting yokes connected to the 65 ends of the respective conducting members, insulating means for supporting the respective yokes, and a plurality of conducting bars attached to the respective yokes, said bars being laterally spaced and extending substantially parallel to the electrodes.
17. In a polyphase liquid rheostat, the combination with a containing tank and a plurality of sets of electrodes assembled in spaced side-by-side relation and corresponding to the several phases, of a corresponding plurality of transversely-extending conducting members connected only to electrodes of the same phase, conducting yokes connected to the 70 ends of the respective conducting members, insulating means for supporting the respective yokes, and a plurality of conducting bars attached to the respective yokes, said bars being laterally spaced and extending substantially parallel to the electrodes.
18. In a polyphase liquid rheostat, the combination with a containing tank and a plurality of sets of electrodes assembled in spaced side-by-side relation and corresponding to the several phases, of a corresponding plurality of transversely-extending conducting members connected only to electrodes of the same phase, conducting yokes connected to the 75 ends of the respective conducting members, insulating means for supporting the respective yokes, a plurality of conducting bars attached to the respective yokes, said bars being laterally spaced and extending substantially parallel to the electrodes, insulating bushings supported in a tank wall and inclosing conducting means, and flexible means for connecting corresponding conducting bars and conducting 80 means.
19. In a polyphase liquid rheostat, the combination with a plurality of sets of electrodes corresponding to the several phases, of a plurality of groups of vertically-aligned conducting rod members, conducting means connected to the outer ends 85 of the respective conducting members, insulating means for supporting the respective yokes, a plurality of conducting bars attached to the respective yokes, said bars being laterally spaced and extending substantially parallel to the electrodes, a plurality of conducting straps interposed between said yokes and certain intermediate electrodes of the corresponding phase, insulating bushings supported in a tank wall and inclosing conducting means, and a plurality of flexible conducting 90 means for connecting corresponding conducting bars and conducting means.
20. In a polyphase liquid rheostat, the combination with a plurality of sets of electrodes corresponding to the several phases, of a plurality of groups of vertically-aligned conducting rod members, conducting means connected to the outer ends of the respective conducting members, insulating means for supporting the respective yokes, laterally spaced conducting bars attached to the respective yokes, and a plurality of other conducting means inter- posed between said yokes and certain intermediate electrodes of the corresponding phase.

of each group of rod members, and means for supporting said last means.

20. A polyphase liquid rheostat embodying sets of electrodes of different lengths for the several phases, the electrodes being arranged in an irregular rotation of phases to provide a smoothly continuous resistance

variation in each phase and substantially uniform decreases of liquid resistance volumes between phases.

In testimony whereof, I have hereunto subscribed my name this 29th day of November 1916.

ARTHUR J. HALL.
